Int. Cl. D7—01

U.S. Cl. D36—2

FIG. 1 is an elevational view of a bowl or similar article, showing my new design, it being understood that the bands of cut ornamentation continue about the entire periphery in the paths indicated;

FIG. 2 is a bottom view thereof;

FIG. 3 is a sectional view taken along line 3-3 of FIG. 1; and

FIG. 4 is a development of the design.

This application is a division of pending design application Ser. No. D. 11,700, filed Apr. 30, 1968.

I claim:

The ornamental design for a bowl or similar article, substantially as shown and described.
